UNITED STATES PATENT OFFICE.

ELIAS P. NEEDHAM AND ORWELL H. NEEDHAM, OF NEW YORK, N. Y.

MECHANICAL MUSICAL INSTRUMENT.

SPECIFICATION forming part of Letters Patent No. 224,716, dated February 17, 1880.

Application filed July 11, 1879.

To all whom it may concern:

Be it known that we, ELIAS P. NEEDHAM and ORWELL H. NEEDHAM, both of the city of New York, in the county and State of New York, have invented certain new and useful Improvements in Mechanical Musical Instruments, of which the following is a specification.

Our invention relates to that class of mechanical wind musical instruments in which pneumatic keys are employed to actuate the sound-producing devices, the operation of the pneumatic keys being preferably controlled by the passage of a perforated or equivalently-prepared music-sheet over apertures in an action-board.

In all wind-instruments it is found that the best results are obtained when air of only a moderate pressure is used to operate the pipes or reeds. Such a pressure, however, might not always be sufficient to actuate pneumatic keys for effecting the various operations necessary for playing—viz., opening valves and working swells and stops, or doing such other mechanical work about an organ or other instrument as may be desirable.

Our invention consists, essentially, in the combination, in a wind-instrument constructed and adapted to be played by pneumatic keys, of two separate wind-chests, one for supplying the air to work the pneumatic keys and another for supplying air to the reeds or pipes, the former containing air of a greater pressure than the latter, and a valve or valves actuated by said pneumatic keys for controlling the emission of air from the wind-chest containing the lesser pressure.

It also consists in novel combinations of parts for adapting pneumatic keys to mechanical musical instruments the playing of which is performed by means of perforated or equivalently-prepared paper.

In the accompanying drawings, Figure 1 represents a central vertical section of a mechanical musical instrument embodying our improvements. Fig. 2 is a transverse section on the dotted line *x x*, Fig. 1; and Fig. 3 is a similar section on the dotted line *y y*, Fig. 1.

Similar letters of reference designate corresponding parts in all the figures.

50 A. B designate two wind-chests or chambers, both of which preferably contain air of a

greater pressure than the atmosphere, and one of which, A, is adapted to contain air of a greater pressure than the other, B.

The chamber A is supplied with air by a duct or passage, A', leading from a receiver, C, which in this instance forms the base of the instrument, and into which air is pumped by a bellows, C', under control of valves *a* and *b*, or by a force-pump. This receiver C is provided with a bellows-like portion, C², which may be acted upon by weights or springs for the purpose of maintaining a uniform pressure of air in the wind-chest A.

The wind-chest B is supplied with air through an aperture, *c*, (see Fig. 2,) communicating with the receiver B', into which air is forced by a bellows, D, under control of valves *d* and *e*. Communicating with the receiver B' is a bellows-like portion, B², which may be acted upon by a weight or springs for the purpose of maintaining a uniform pressure of air in the wind-chest B; and in order to prevent the pressure within it from increasing beyond a certain point the said receiver is provided upon its top with an outwardly-opening valve, *f*, (here represented as a pallet-valve,) which, when the air increases beyond the desired pressure, opens against the force of a spring or weight. (Not here represented.)

Instead of maintaining a pressure of air in the wind-chest B, the air may be exhausted therefrom.

For convenience of operation the two bellows C' and D may be connected at their sides, as represented at *g*, so as to be operated simultaneously. In lieu of these bellows, force-pumps might be employed.

E designates an action-board, which communicates with and may be placed within the wind-chest A; and F designates a perforated music-sheet secured to rollers G, and adapted to be fed from one to another of said rollers over said action-board. The action-board has in it a series of ducts or passages, *h*. (Here represented as three in number, and each communicating with a chamber, H, shown as arranged below the wind-chests A and B.)

In lieu of a perforated music-sheet, a sheet having recesses in or projections upon it, which act upon jacks or levers for opening the passages in the action-board, may be employed.

Within each of the chambers H is arranged a pneumatic key, H', adapted to be forced upward by the pressure of air below it, and communicating with the atmosphere through an 5 aperture, i, to permit of its free movement. Although these pneumatic keys H' are represented as hinged at j, they may be constructed in any desirable manner—as, for instance, adapted to be raised bodily by the action of 10 the air below them; or they may be made in the form of bellows.

I designates a series of pallet-valves, corresponding in number with the pneumatic keys H'; and I' designates push-pins, which communicate motion from the pneumatic keys to the valves I. When the said valves I are opened by the action of the said pneumatic keys the air contained in the wind-chest B passes through the ducts or passages k to the 20 pipes J or other sound-producing devices—such, for instance, as reeds.

In addition to the ducts or passages h, leading to the pneumatic keys, I have shown the action-board as provided with other ducts or 25 passages, l, communicating through the horizontally-arranged ducts l' with the chambers K, in which are placed other pneumatic keys, L, which, through push-pins m, may operate at n in the drawings, or one or more swells, M. 30 (See Fig. 3.) In addition to these, other pneumatic keys might be employed to operate stops or perform any desired mechanical work about a musical instrument. Although the pneumatic keys L may be made to operate similarly to the keys H', they are here represented as plunger-like in form, and are adapted to be raised bodily by the pressure of air below them. To render the action of the keys L 35 more sensitive, we prefer to recess or hollow out the said keys on their under sides, as clearly represented in Fig. 3, so as to allow the air to spread throughout its whole extent.

By our invention the air for operating the pipes or reeds may at all times be maintained 45 at a uniform pressure, regardless of the pressure of air required to work the swells, stops, or other mechanical devices.

What we claim as our invention, and desire to secure by Letters Patent, is—

50 1. In a mechanical musical instrument constructed and adapted to be played by pneumatic keys, the combination of two separate wind-chests, one for supplying air to work the pneumatic keys and another for supplying air 55 to the reeds or pipes, the former containing air of a greater pressure than the latter, and a valve actuated by said pneumatic keys for controlling the emission of air from the wind-chest containing the lesser pressure, substantially 60 as specified.

2. In a mechanical musical instrument constructed and adapted to be played by pneumatic keys, the combination, with two separate wind-chests—one for supplying air to work the pneumatic keys and another for supplying air to the reeds or pipes, the former for containing air of a greater pressure than the latter—of an action-board, a perforated or equivalently-prepared music-sheet passing over said action-board, whereby the passage of 65 air from the wind-chest to the pneumatic keys is controlled, and a valve or valves actuated by said pneumatic keys for controlling the emission of air from the wind-chest containing the lesser pressure, substantially as specified. 70

3. In a mechanical musical instrument constructed and adapted to be played by pneumatic keys, the combination, with the separate wind-chests, one for supplying air to work the pneumatic keys and the other for supplying air to the reeds or pipes, the former containing air of a greater pressure than the latter, of an action-board and a perforated or equivalently-prepared music-sheet, both arranged in the wind-chest containing the greater 85 pressure, and serving to control the operation of the pneumatic keys, and a valve or valves actuated by said pneumatic keys for controlling the emission of air from the wind-chest containing the lesser pressure, substantially 90 as specified.

4. The combination, with a pneumatic key, of a pressure or blowing bellows or pump for operating the same, a wind-chest supplied by said bellows, an action-board, and a perforated 95 music-sheet, also arranged within said wind-chest and passing over openings in said board communicating with said keys, substantially as specified.

5. In a mechanical musical instrument, the 100 combination of two wind-chests and pumps or pressure-bellows for keeping them so filled or supplied with air that the air in one is at a greater pressure than that in the other, valves for controlling the communication between the wind-chest which is to contain the lesser pressure and the pipes or reeds, an action-board in communication with the wind-chest which is to contain the greater pressure, and a perforated or equivalently-prepared 105 music-sheet arranged to work over openings in the said action-board.
